UNITED STATES PATENT OFFICE

149,969

DESIGN FOR A ROTARY MOWING MACHINE

William H. Phelps, Ralston, Nebr.

Application July 17, 1946, Serial No. 131,655

Term of patent 14 years

(Cl. D40—1)

To all whom it may concern:

Be it known that I, William H. Phelps, a citizen of the United States, residing at Ralston, county of Douglas, and State of Nebraska, have invented a new, original, and ornamental Design for a Rotary Mowing Machine, of which the following is a specification, reference being had to the accompanying drawing, forming a part thereof, in which:

Figure 1 is a plan view of a rotary moving machine showing my new design; Figure 2 is a side elevational view; Figure 3 is a perspective view of the right front of the machine; and Fig. 4 is a perspective view of the left rear of the machine.

I claim:

The ornamental design for a rotary mowing machine, as shown.

WILLIAM H. PHELPS.
